R. PORTER.

Fog Signal.

No. 15,085.

Patented June 10, 1856.

UNITED STATES PATENT OFFICE.

RUFUS PORTER, OF WASHINGTON, DISTRICT OF COLUMBIA.

MODE OF SOUNDING WHISTLES FOR FOG-SIGNALS.

Specification of Letters Patent No. 15,085, dated June 10, 1856.

To all whom it may concern:

Be it known that I, RUFUS PORTER, of Washington, in the District of Columbia, have invented a new and useful Sonorific 5 Beacon; and I do hereby declare that the following is a full and exact description of the same, reference being had to the annexed drawings, making part of this specification, in which—

10 Figures 1, 2, and 3 are vertical sections of different forms of whistles to be employed in this apparatus; Fig. 4 represents the upper portion of a vertical cylinder to the head of which is attached a circle of whistles 15 of different kinds; Fig. 5 is an elevation of a sonorific beacon erected upon a shoal; Fig. 6 is an elevation of the same erected upon a rock; Fig. 7 is a profile of a floating beacon moored upon a shoal, and Fig. 8 is a 20 vertical view of the same.

The nature of this invention consists in attaching suitable whistles (or trumpets) to the heads of strong vertical cylinders, and adjusting and securing the same in vertical 25 positions, and in such manner that the waves or swells of the sea will produce loud and shrill sounds, for the purpose of indicating, and giving notice to mariners, of the location of dangerous rocks or shoals.

30 The cylinders A and N may be made of galvanized iron or other metal, and secured in upright positions by means of three inclined posts B B B, fastened together at the top, as represented in Fig. 5, or supported by a 35 strong vertical post P, firmly set in a rock, and passing up through the center of the cylinder, as represented in Fig. 6. These cylinders may be twelve or fifteen inches in diameter and twenty-five feet long, the bottom 40 toms being open, and extending as low as the surface of low water. To the head of each cylinder are attached vertical whistles c c, and the whole surmounted by a conspicuous metal-plate signal D. Moreover, 45 the cylinders are furnished with interior clapper-valves E, near the heads thereof, which admit the air when the water recedes, but prevents its escape when the water rises.

The cylinder A is secured in its position by horizontal braces m m. (In some cases 50 it may be expedient to elevate one or more whistles, several feet above the head of the cylinder, with which they may communicate by a tube, as represented at I J Fig. 5.) Another mode of employing the undulation whistle, and constructing a sonorific beacon, is to attach a small whistling cylinder F G, to each end of a long spar M, and moor the same by chains to a rock (or anchor) H; the chain or hawser being connected to the spar at about one third of its length from one end thereof, in consequence of which, the spar will take a position in the direction of the wind or waves. To this spar may be attached a cross-spar (K, Fig. 65 8) but this arrangement is not supposed to be of much utility.

The whistles attached to the cylinders at the ends of the spar, will give shrill sounds as often as the cylinders are plunged into 70 the water. These cylinders may be two feet long by eight inches in diameter; and they will not require valves, as they are so adjusted as to be raised out of water, at the intervals of the waves.

The elevated whistles may be shielded from the snow or sleet storms, by having inverted cups placed over them; but the floating and plunging cylinders will require no such protection.

The sounds are produced by the escape of air from the cylinders, in consequence of the undulation of the water. Some of the whistles will give sound by small waves, while others are much louder, but require 85 heavier waves.

I claim—

The combination of vertical cylinders (or their equivalents) and whistles attached thereto, for the purpose of having loud 90 sounds produced by the undulation of waves or swells, substantially as herein described.

RUFUS PORTER.
